PENCIL POINTER

Frederick Burnham Chapman,
South Hamilton, Mass.

Application March 20, 1946, Serial No. 655,788

5 Claims. (Cl. 120—89)

1

This invention relates to a device for pointing pencils, crayons and the like writing or drawing implements.

In various types of drafting it is desirable to use a pencil or crayon having a properly pointed end in order to draw the desired type of line, and it is the customary practice for a draftsman or artist to rub the point against a sheet of sandpaper, a flat file or the like abrasive member while holding the pencil at the proper angle. The accumulations of ground graphite or crayon that necessarily result from such practice is apt not only to soil the fingers, but also to be blown or carried onto the work with the consequent formation of smudges, etc., which are difficult to remove without obliterating or impairing the drawings. Moreover, the used abrasive constitutes a nuisance which must be kept away from the work and drafting implements in order to avoid the above-mentioned difficulties.

The principal object of the present invention is to provide a simple and efficient device which is capable of forming any one of several different points on a pencil or crayon and which at the same time prevents accumulations of ground graphite or crayon from soiling the fingers and from fouling or otherwise interfering with the work.

Further objects relate to various features of construction and will be apparent from a consideration of the following description and accompanying drawings which disclose what is now considered a preferred embodiment of the invention, and wherein:

Fig. 1 is a side elevation of the pencil pointer;

Fig. 2 is an end elevation of the outer member or casing;

Figs. 3 and 4 are side and end elevations, respectively, of the inner member or tray;

Figs. 5 and 6 are side and end elevations, respectively, of the winding key; and

Fig. 7 is an end view of the assembled device.

The embodiment herein shown comprises a sheet metal casing 1 having a bottom wall 2 and upwardly convergent side walls 4 and 5, the upper ends of which are bent outwardly to provide scroll-like members 6 and 7 of generally cylindrical cross section which are normally disposed in approximate tangential relation with each other. The sides 4 and 5 normally hold the scrolls 6 and 7 in contact under slight pressure, but are sufficiently resilient to permit the scrolls to be sprung apart to provide a gap 8 (Fig. 2) at the approximate line of tangency of the scrolls. The end portions of the scrolls are somewhat convergent, as shown by the dotted lines of Fig. 1, and terminate in spaced relation to the outer faces of the side walls to provide gaps 9 and 10, as shown in Figs. 2 and 7. The scrolls 6 and 7 support rolls of abrasive sheet material 11 and 12, such as a medium emery cloth or sandpaper, the free end portions of which pass through the gaps 9 and 10, then about the outer surfaces of the scrolls with their abrasive faces exposed and downwardly through the gap 8 into the interior of the casing 1, as shown in Fig. 7.

10 A tray 12 (Figs. 3 and 4) having shallow side walls and upstanding end walls 14 and 15, here shown as approximately triangular in shape to conform with the open ends of the casing 1, is slidable into and out of the casing so that when assembled therewith the end walls 14 and 15 provide closures for the ends of the casing. At corresponding parts adjacent to their rear ends, the bottom walls of both the casing and tray are formed with struck-up ribs 13 and 13^a (Figs. 2 and 4) which provide interengageable releasable locking members for holding the tray within the casing. The end walls 14 and 15 are formed with horizontally aligned openings 16 and 17 (Figs. 3 and 4) which define bearings for rotatably supporting a winding key or mandrel 18 (Figs. 5 and 6). The marginal portion about the opening 16 is slit radially to form resilient detents 20 which are bent inwardly to provide, in effect, locking ratchets acting on the adjacent end of the winding key to prevent rotation thereof in one direction. The opening 17 communicates with a transverse slot 21 (Figs. 4 and 7) which permits the winding key to be readily applied to and removed from the tray.

15 The winding key 18 is preferably formed from a single piece of heavy wire and its body portion is flattened and provided with a slot 24 which receives the ends of the abrasive sheets 11 and 12. The end 25 of the winding key snugly fits the opening 16 with the shoulder defined by the junction of end 25 and body portion 22 engageable with the detents 20, and the opposite end 26 of the winding key is slidable through the slot 21 into opening 17, the construction and arrangement of parts being such that when assembled with the tray 12 the opposite ends of the body portion 22 are in engagement with the inner faces of the end walls surrounding the openings 16 and 17, thereby preventing axial movement of the key. The end 26 is formed with an extension bent to provide a loop or handle 28 by means of which the key may be rotated in one direction to wind up the used abrasive sheets 11 and 12 about its body portion 22.

20 To assemble the device the ends of a pair of rolls 11 and 12 of abrasive sheets are first inserted through the slot 24 of the winding key, the inserted ends being bent about the body of the key so as to insure adequate anchorage thereto. While holding the assembled rolls and key, the latter is inserted in position in tray 12 which may then be slid into the casing 1, the rolls 11 and 12 being held so that the wound up parts simul-

taneously enter the interior of the scrolls 6 and 7 and the intermediate or unwound parts pass through the gaps 8, 9 and 10, it being noted that the convergent ends of the scroll facilitate such assembly and the proper centering of the rolls. When thus assembled the rolls 11 and 12 are supported within the scrolls 6 and 7, respectively, their unwound or free end portions passing through gaps 9 and 10 about the outer face of the scrolls with their abrasive surfaces exposed, then downwardly through gap 8 to the winding key 18, as shown in Fig. 7. By manipulating either the rolls 11 and 12, or the winding key 18, the abrasive sheets may be drawn and held taut about the outer faces of the scrolls.

In using the device the worn or unpointed end of a pencil or crayon is inserted into the bight or line of approximate tangency of the scrolls defined by gap 8 and drawn back and forth in contact with the abrasive surfaces, the pencil or crayon being held at the desired angle, relative to the plane passing through the axes of the scrolls, with or without being simultaneously rotated, depending upon the type of point desired. The accumulations of ground graphite or crayon thus produced are deposited on the abrasive sheets and by turning the key 18 through a small angle (say 30°, counterclockwise in Fig. 7), the used surfaces of the abrasive sheet are drawn downwardly into the casing, thereby not only presenting fresh surfaces of abrasive sheets adjacent to the approximate line of tangency, but also effectively disposing of the accumulations of ground graphite or crayon, it being noted that such accumulations are "sealed in" between the abrasive sheets where they cannot be dislodged or accidentally blown away.

When the abrasive sheets have been used the tray 12 may be withdrawn from the casing 1 and the key 18 together with the used sheets of abrasive wound thereon may then be removed and discarded. Fresh rolls of abrasive sheets and a new or recovered key may then be coupled and the parts assembled as above described.

While I have shown and described one desirable embodiment of the invention, it is to be understood that this disclosure is for the purpose of illustration, and that various changes in shape, proportion and arrangement of parts, as well as the substitution of equivalent elements for those herein shown and described, may be made without departing from the spirit and scope of the present invention as set forth in the appended claims.

I claim:

1. A pencil pointer comprising a casing having at its upper part a pair of generally cylindrical members disposed in approximate tangential relation with each other, a sheet of abrasive material extending about the surface of each of said members and downwardly between said members with its end portion within said casing, and a winding key rotatably supported within said casing, the end portions of the abrasive sheets being secured to said key so that upon rotation thereof fresh surfaces of said abrasive sheets are presented adjacent to the approximate line of tangency of said members.

2. A pencil pointer comprising a casing, a removable tray disposed within said casing, a pair of generally cylindrical members carried by the upper end of said casing and disposed in approximate tangential relation with each other, a sheet

of abrasive material extending about the surface of each of said members and downwardly between said members with its end portion within said casing, and a winding key having its end portions rotatably supported by opposite ends of said tray, the ends of the abrasive sheets being secured to said key so that upon rotation thereof fresh surfaces of said abrasive sheets are presented adjacent to the approximate line of tangency of said members.

3. A pencil pointer comprising a casing of sheet material having side walls converging at their upper ends and bent outwardly to form a pair of scroll-like members of generally cylindrical cross section in approximate tangential relation with each other, a roll of abrasive sheet material disposed within each scroll-like member, the abrasive sheet material of each roll extending about the outer face of the scroll-like member and downwardly between the scroll-like members into the interior of said casing, and means for moving the sheets of abrasive material downwardly into the interior of said casing so as to present fresh surfaces thereof adjacent to the approximate line of tangency of said scroll-like members.

4. A pencil pointer comprising a casing of sheet material having side walls converging at their upper ends and bent outwardly to form a pair of scroll-like members of generally cylindrical cross section in approximate tangential relation with each other, a roll of abrasive sheet material disposed within each scroll-like member, the abrasive sheet material of each roll extending about the outer face of the scroll-like member and downwardly between the scroll-like members into the interior of said casing, and a winding key rotatably supported within said casing, the ends of the abrasive sheets being secured to said key so that upon rotation thereof fresh surfaces of the abrasive sheets are presented adjacent to the approximate line of tangency of said scroll-like members.

5. A pencil pointer comprising a casing of sheet material having side walls converging at their upper ends and bent outwardly to form a pair of scroll-like members of generally cylindrical cross section in approximate tangential relation with each other, a roll of abrasive sheet material disposed within each scroll-like member, the abrasive sheet material of each roll extending about the outer face of the scroll-like member and downwardly between the scroll-like members into the interior of said casing, a tray slidably into and out of said casing, a slotted key having its end portions rotatably supported by opposite ends of said tray, the ends of said abrasive sheet passing through the slotted key and being secured thereto so that upon rotation of said key the abrasive sheets are drawn over said scroll-like members and into the interior of said casing, and means for preventing rotation of said key in one direction.
